WEIGHING AND FILLING MACHINE

Original Filed March 20, 1924 2 Sheets-Sheet 2

Patented May 10, 1927.

UNITED STATES PATENT OFFICE.

LEWIS D. NELSON, OF COLDWATER, MICHIGAN, ASSIGNOR OF ONE-HALF TO ROBERT M. NEALE, OF UNION CITY, MICHIGAN.

WEIGHING AND FILLING MACHINE.

Original application filed March 20, 1924, Serial No. 700,567. Divided and this application filed August 17, 1925. Serial No. 50,722.

This invention relates to improvements in weighing and filling machines.

My improvements are especially designed by me for embodiment in bag filling machines for lime, cement and like materials and I have shown my improvements as I have embodied them for that purpose. They are, however, readily adapted and desirable for use in various other relations.

10 The main objects of this invention are: First, to provide an improved bag filling machine which is automatic in its operation and at the same time quite simple in structure.

15 Second, to provide an improved filling machine of very large capacity.

Third, to provide an improved bag filling machine which requires but little effort on the part of the operator.

20 Objects pertaining to details and economies of construction and operation of my invention will definitely appear from the detailed description to follow.

I accomplish the objects of my invention 25 by the devices and means described in the following specification. The invention is clearly defined and pointed out in the claims.

A structure embodying the features of 30 my invention is clearly illustrated in the accompanying drawing forming a part of this application, in which:

Fig. I is a front elevation of a structure embodying the features of my invention, 35 portions of the hopper and base being broken away.

Fig. II is a fragmentary side elevation looking from the right of Fig. I.

Fig. III is a detail front elevation corresponding to that of Fig. I with the parts in another position.

Fig. IV is a fragmentary front elevation of the parts shown in Fig. III showing them in another position.

45 Fig. V is a fragmentary view mainly in vertical section on line 5—5 of Fig. I.

In the drawing similar reference numerals indicate similar parts in all of the views.

Referring to the drawing, I provide a 50 frame consisting of a base 1 and pedestal 2 mounted thereon carrying the hopper 3 and the ejector cylinder 4. Within the ejector cylinder is a feed rotor designated generally by the numeral 5. This rotor is illus-

trated and described in detail in my application for Letters Patent, Serial No. 700,567, filed March 20, 1924, of which application this is a division. The rotor cylinder has a discharge passage 6.

The machine is designed to deliver to 60 valve bags 8 which are slipped upon the spouts 7, the upper end of one of the bags 8 being indicated by dotted lines in Fig. V. A pair of these spouts 7 is provided, the spouts being adjustably mounted at 9 on a 65 carrier 10 which is supported for oscillating movement so that the spouts are alternately brought into registering relation with the discharge passage 6.

The carrier 10 is pivotally mounted on 70 the scale beam 11, the scale beam being pivoted at 12 and having a weight 13 at its outer end. The carrier 10 is pivoted on the scale beam at 14 and is provided with a yoke 15 at its upper end with which the actuating lever 16 coacts, the lever being pivoted at 17 and provided with a roller 18 engaging the yoke. The yoke is provided with seats 19 at its ends.

The lever 16 is actuated by the spring 20 80 which slidably engages the slotted arm 22 on the upper end of the lever. With the parts thus arranged, when the member 10 is raised the spring is placed under stress storing power for actuating the lever. 85 When the carrier is lowered as by the tilting of the scale beam under the weight of the filled bag, the lever is swung by the spring to the opposite end of the yoke, thereby oscillating or swinging the carrier. 90

The carrier is provided with two ports 23 adapted to alternately register with the feed passage 6, the carrier during its oscillating movement constituting a valve for the passage so that it is a combined valve 95 and spout carrier.

It is intended that the operator shall place a bag upon the spout in inoperative position while a bag is being filled so that as soon as the discharge passage is uncovered a bag is in 100 position to receive it. A platform 24 pivotally and slidably mounted at 25 is provided for supporting the bags, the pivots being slidably supported by the plates 26 having vertical slots 27 therein. The pivots are 105 carried by the platform hangers 28 which are carried by the scale beam.

The platform is supported in its erected

position by the latch 29 on the hanger which is held in engaging position with the keeper 30 on the platform by means of the spring 31. On the downward movement of the platform occasioned by the tilting of the scale beam, this latch comes in contact with the trip 32 releasing the latch and allowing the platform to tilt and discharge the filled bags into the chute 33. The downward movement of the scale beam also releases the spouts so that the spouts tilt substantially simultaneously with the tilting of the platform to discharge the bags.

The spouts are held in their erected position by the keeper arm 34 under which the upwardly projecting arms 35 on the spouts project when the spouts are in filling position; that is, the arms alternately swing under the keeper as the member 10 oscillates. When the carrier moves downwardly the arms 35 pass from under these keepers allowing the spouts to tilt. After the bags are discharged the spouts are returned to their erected position by the coiled springs 37. The arm 34 is provided with a thrust bearing 38 under which the member 10 oscillates.

The platform is returned to its erected position by the counterweight 39 projecting into an opening 40 in the pedestal, see Figs. I and II where the platform is shown in erected and discharging positions.

My improved filling machine is of very large capacity and the labor in operating the same is minimized.

I have illustrated and described my improvements as I have embodied the same in a device which I have found very practical. I have not attempted to illustrate or describe certain embodiments or adaptations which I contemplate as I believe the disclosure made will enable those skilled in the art to embody or adapt the same as may be desired.

Having thus described my invention what I claim as new and desire to secure by Letters Patent is:

1. In a structure of the class described, the combination of feed means having a feed opening, a weighing mechanism comprising a scale beam, a combined carrier and valve member mounted on said scale beam for oscillating and vertical movement, spouts pivotally mounted on said member to be alternately brought into operative relation to said feed opening, a keeper with which said spouts engage when in operative position, means for releasing said spouts from said keeper on the downward movement of said member, a tilting platform carried by said scale beam, a latch for holding said platform in erected position, and a trip with which said latch is engaged on the downward movement of said platform.

2. In a structure of the class described, the combination of feed means having a feed

opening, a weighing mechanism comprising a scale beam, a combined carrier and valve member mounted on said scale beam for oscillating and vertical movement, spouts pivotally mounted on said member to be alternately brought into operative relation to said feed opening, and a keeper with which said spouts engage when in operative position, means for releasing said spouts from said keeper on the downward movement of said member.

3. In a structure of the class described, the combination of feed means having a feed opening, a weighing mechanism comprising a scale beam, a combined carrier and valve member mounted on said scale beam for oscillating and vertical movement, spouts mounted on said member to be alternately brought into operative relation to said feed opening, a tilting platform carried by said scale beam, a latch for holding said platform in erected position, and a trip with which said latch is engaged on the downward movement of said platform.

4. In a structure of the class described, the combination of feed means having a feed opening, a weighing mechanism comprising a scale beam, a combined carrier and valve member mounted on said scale beam for oscillating and vertical movement, and spouts mounted on said member to be alternately brought into operative relation to said feed opening.

5. In a structure of the class described, the combination of a weighing mechanism, a combined spout carrier and feed control member mounted on said weighing mechanism for oscillating and vertical movement, spouts pivotally mounted on said member to be alternately brought to operative position, a keeper with which said spouts engage when in operative position, means for releasing said spouts from said keeper on the downward movement of said member, a tilting platform, and means for holding said platform in erected position controlled by said weighing mechanism.

6. In a structure of the class described, the combination of a weighing mechanism, a combined spout carrier and feed control member mounted on said weighing mechanism for oscillating and vertical movement, spouts pivotally mounted on said member to be alternately brought to operative position, and a keeper with which said spouts engage when in operative position, means for releasing said spouts from said keeper on the downward movement of said member.

7. In a structure of the class described, the combination of a weighing mechanism, a feed means, a combined spout support and feed control member mounted for oscillating and vertical movement and operatively associated with said weighing mechanism, and spouts mounted on said members to be alter-

nately brought into operative relation to feed control member, means for actuating said feed means.

8. In a structure of the class described, the combination of a weighing mechanism, 5 a feed means, a combined spout carrier and feed control member, means for actuating said member operatively associated with said weighing mechanism, spouts mounted on said member to be alternately brought to operative relation to said feed means.

10. In a structure of the class described, 25 the combination of a weighing mechanism, a feed means, a combined spout support and feed control member operatively associated with said weighing mechanism, and spouts mounted on said members to be alternately brought into operative relation to said feed means.

15. In a structure of the class described, 20 the combination of a weighing mechanism, a feed means, a combined spout carrier and

means for actuating said feed means, a tilting platform for supporting the receptacles to which the spouts deliver carried by said weighing mechanism and means for holding said platform in erected position controlled by said weighing mechanism.

9. In a structure of the class described, 15 the combination of a weighing mechanism, a feed means, a combined spout carrier and

means for actuating said feed means.

In witness whereof I have hereunto set

my hand.

LEWIS D. NELSON.
